UNITED STATES PATENT OFFICE

ARTHUR L. NUNN, OF FULLERTON, CALIFORNIA

DESIGN FOR A BASEBALL GAME BOARD

Application filed October 31, 1932. Serial No. 45,869. Term of patent 7 years.

To all whom it may concern:

Be it known that I, ARTHUR L. NUNN, a citizen of the United States, residing at Fullerton, in the county of Orange and State of California, have invented a new, original, and ornamental Design for a Baseball Game Board, of which the following is a specification, reference being had to the accompanying drawing, forming part thereof.

Figure 1 is a perspective view of the game-board in position for play;

Figure 2 is a partial side view of the same.

I claim:

The ornamental design for a baseball game board, as shown.

ARTHUR L. NUNN.
